UNITED STATES PATENT OFFICE.

WILLIAM H. ADAMS, JAMES D. FELTHOUSEN, AND ALBERT LAWTENSLAGER,
OF ALBANY, NEW YORK.

CAR-COUPING.

SPECIFICATION forming part of Letters Patent No. 339,358, dated April 6, 1886.

Application filed February 3, 1886. Serial No. 190,724. (No model.)

To all whom it may concern:

Be it known that we, WILLIAM H. ADAMS, JAMES D. FELTHOUSEN, and ALBERT LAWTENSLAGER, all of Albany, in the county of Albany and State of New York, have invented 5 a new and useful Improvement in Car-Couplings, of which the following is a full, clear, and exact description.

Reference is to be had to the accompanying 10 drawings, forming a part of this specification, in which similar letters of reference indicate corresponding parts in all the figures.

Figure 1 is a sectional side elevation of our 15 improved car-coupling, part being broken away. Fig. 2 is a front elevation of one of the draw-heads, the coupling-links being shown in section. Fig. 3 is a sectional plan view of a part of the coupling, taken through the line *a a*, Fig. 2.

20 The object of this invention is to improve the construction of the car-couplings for which Letters Patent No. 305,261 were issued to us September 16, 1884, in such a manner as to make them more reliable in operation.

25 The invention consists in the construction and combination of various parts of the car-coupling, as will be hereinafter fully described and claimed.

30 A represents the draw-head of the car-coupling, which is made with a flaring mouth, so that the coupling-link B will enter it with certainty.

35 The coupling-head A is designed to be secured to the car in the ordinary manner. In the top of the coupling-head A is formed a slot, C, of sufficient size to allow the coupling-hook D to be readily inserted and removed through it. In the rear end of the hook D is formed a short slot, E, to receive the pin F, 40 by means of which the said hook is secured in place. The pin F can be kept in place by a key or other suitable means, and should be so arranged as to allow the coupling-head A to have the necessary play.

45 The coupling-hook D is made with two hooks, G H, upon its lower side, which enter slots I J in the lower side of the draw-head A. The rear hook, H, is made long, so that it will never be raised out of its slot J when 50 the car-coupling is in use.

The forward upper corner of the coupling-

hook D is beveled or inclined to fit against the beveled seat K at the forward end of the slot C, so that a draft strain upon the said hook will hold it more firmly in place and 55 prevent it from jumping upward and releasing the coupling-link.

The forward side of the forward hook, G, is inclined or rounded, so that the hook D will be raised by the contact of the coupling-link 60 B when the cars are run together to allow the end of the said link to pass the forward hook, G, when the coupling-hook D drops back into place and the cars are coupled, the forward hook, G, passing through the said link B. 65

The inclined forward side of the forward hook G rests against an inclined seat, L, at the forward end of the slot L. The forward side of the rear hook, H, is inclined or rounded, and rests against an inclined seat, M, at 70 the forward end of the slot J, so that the coupling-hook D is provided with four bearing-points, the inclined seats K L M, and the pin F.

75 With this construction each draw-head A is permanently provided with a coupling-link, B, the inner end of which is held by the rear hook, H, of the double hook D, and which, when two cars are run together, enters the draw-head of the adjacent car, raises the coupling-hook D, and passes and engages with the forward hook, G, so that the draft strain will be sustained by two independent links, either of which will sustain the draft strain should the other link be broken. 80

85 With this construction, should both the links B be broken, the cars can be coupled by an ordinary coupling-link, the ends of which engage with the forward hooks, G, of the double hooks D, and with this arrangement the coupling will still be automatic. 90

95 In recesses in the sides of the draw-head A, upon the opposite sides of the shank of the coupling-hook D, and in front of the pin F, are placed loose weights N, the forward parts 100 of which rest upon the inner end of the coupling-link permanently connected with the said draw-head, and which should be of sufficient gravity to hold the other end of the said link raised, so that it will enter the draw-head of an adjacent car automatically. The forward movement of the weights N is prevented by

ribs O, formed upon the inner surfaces of the sides of the draw-head A. The links B are held against the rearward push when the cars are run together, and the forward ends of the 5 said links strike the hooks of the adjacent cars by shoulders P, formed upon the inner surfaces of the sides of the draw-head A.

Having thus fully described our invention, we claim as new and desire to secure by Letters 10 Patent—

1. The combination, with the draw-head formed with the open flaring mouth, the top slot, C, the bottom slots, I J, the weight-recesses on its inner sides, and the ribs O, projecting from said inner sides in front of the 15 said recesses, of the weights N in said recesses, the pin F in rear of the recesses, the coupling-hook D, having a shank projecting rearward between the ribs O to its pivot-pin 20 F, and having the two hooks G H at its for-

ward end, and the permanent link B, substantially as set forth.

2. In a car-coupling, the combination, with the draw-head A, having slots C I J, and beveled seats K L M at the forward 25 ends of the said slots, of the double hook D, beveled at the upper part of its forward end, and having a short forward hook, G, and a longer rear hook, H, on its lower side, and the fastening-pin F, substantially as herein 30 shown and described, whereby two coupling-links can be connected independently with the said draw-head, as set forth.
